UNITED STATES PATENT OFFICE.

GEORGE R. CORNWALL, OF RYE, NEW YORK, ASSIGNOR TO AMERICAN PLANOGRAPH COMPANY, OF NEW YORK, N. Y., A CORPORATION OF WEST VIRGINIA.

PROCESS OF PREPARING TRANSFER-SURFACES FOR RECEIVING PRINTING IMPRESSIONS.

No. 852,708.

Specification of Letters Patent.

Patented May 7, 1907.

Application filed May 28, 1903. Serial No. 159,092.

To all whom it may concern:

Be it known that I, GEORGE R. CORNWALL, a citizen of the United States, residing at Rye, in the county of Westchester and State 5 of New York, have invented a new and useful Process of Preparing Transfer-Surfaces for Receiving Printing Impressions, of which the following is a full and complete specification.

My invention relates to printing or making impressions upon a transfer surface, from which the impressions are subsequently transferred to a lithographic or planographic printing surface from which latter an indefinite number of reproductions may be obtained in the well known manner employed in lithography or planography; and my invention has for an object to obtain impressions upon the transfer surface which shall always be clearly and sharply defined and not faint 20 or blurred. This and other objects of invention will more fully appear hereinafter.

The material of which transfer surfaces are usually composed are hygroscopic in character, or comprise an ingredient possessing hygroscopic properties. The free and extensive absorption of moisture by the material of which the transfer surface is composed appears to be useful and necessary in the transferring operation, the transfer of the 25 printed characters from one surface to the other being probably accomplished largely by the dissolution of the material of which the transfer surface is composed.

The hygroscopic property of the transfer surface, while it is useful and perhaps necessary in the operation of transferring, as above indicated, also causes the transfer material to absorb moisture from the atmosphere prior to the printing operation. This 30 is especially the case during periods of great atmospheric humidity. The ink usually employed in printing upon such surfaces for transferring to surfaces adapted to be prepared for printing planographically is of a 35 greasy nature. It is therefore obvious that if the transfer surface absorbs a considerable quantity of moisture prior to the printing operation, or carries a film of moisture, that there will not be good adhesion of the greasy 40 ink upon the said surface and consequently faint and insufficient printing of the characters, and the slight imprint secured is also frequently blurred. It is therefore necessary

to temporarily neutralize the hygroscopic properties of the transfer impression surface 55 and prevent the formation thereon of a film of moisture, or if said film be formed, as above indicated, to remove the moisture and preserve a dry surface for receiving the impression in order to secure satisfactory results from the printing and transferring operations. The remedying of these defects generally in the manner indicated is contemplated by this invention.

The invention is applicable to various 65 forms of printing means for printing upon transfer surfaces, and is herein shown as applied to a composing machine of the type which prints character by character. In connection with such a machine, and in the 70 accompanying drawing I have illustrated an apparatus for carrying out my process.

1 indicates a type carrier, from which impressions are taken, which impressions are taken upon a transfer sheet, indicated at 8. 75 In the drawing the type carrier is shown in the form of a type wheel, having the type arranged around its periphery. Mounted so as to contact with said type wheel are suitable inking rolls 2, 2 which supply the type 80 with ink. A platen 3 is mounted upon a carriage 4, which carries feed rolls 5, whereby the transfer or impression-receiving paper is moved from time to time to print a new line, and the carriage is also provided with suitable means (not shown) for imparting longitudinal movement thereto along the line of printing, on guides 12. These devices being of any usual or suitable kind and well known in typographic or typewriting arts, it is not 85 deemed necessary to show the same in detail, as they form no part of my present invention.

The impressions are made by giving the platen 3 a movement toward the type wheel. The means for accomplishing such movement are here shown as consisting of a toggle 6, one end of which is pivotally secured to a stationary portion of the machine frame and the other end secured to the carriage. To the knuckle of the toggle is connected a tie rod 7, the lower end of which is connected with an eccentric, as shown. Upon rotation of the shaft on which the eccentric is mounted the toggle is operated through the medium of the rod 7, and the carriage is given an impression movement toward the type. It 90 95 100 105

will be understood that the type carrier 1 is arrested at suitable times to bring the desired type opposite the impression point.

- For the carrying out of my invention I provide a source of air or gas supply 11, which may consist of a pump or blower, and from which leads a pipe or conduit 10, terminating in a nozzle or delivery outlet 10', which directs the current of air or gas supplied by the pump or blower upon the surface of the transfer paper, preferably at a point somewhat in advance of the impression point, so as to pass over the surface at the place of impression and circumjacent thereto. Before reaching the delivery outlet the air or gas may be made to pass through a desiccator 14, arranged in its path. The desiccating means in said chamber may consist of any suitable desiccating agent, calcium chloride being an example of such an agent. Also there may be arranged in the course of said air or gas conduit or pipe a device 13, for altering the temperature of the air or gas. This may be either a cooling or heating device. It is preferable, however, to employ means for warming or heating the air, since this augments the drying action thereof and makes it more effective. This heating means may consist, as shown, of a coil of pipe 10, arranged in a suitable chamber so as to be surrounded by a heating medium. A valve 10^x is provided near the delivery outlet of the pipe 10, to control the delivery of the dried and warmed air or gas.
- From the above description it will be seen that my invention consists in applying to the transfer surface, just in advance of and at the point of impression, a moisture-removing medium which temporarily neutralizes the hygroscopic action of the transfer impression surface and prevents the formation thereon of a film of moisture; or if said film be formed it removes the moisture and preserves a dry surface for receiving the impression.
- It will be apparent that any moisture-removing medium may be employed, such for instance as a dust or desiccating powder, which may be blown on the transfer surface by a current of air and afterward removed.
- According to the conditions of the atmosphere the air current employed may be heated or cooled by means of the device 13, as described. It will generally, however, be preferable to heat the air current.
- As a result of my process the transfer surface is at all times preserved in the best condition for receiving and taking the impressions, so that the impressions are always sharp and clear, irrespective of the condition

of the atmosphere and the length of time the transfer surface may be exposed thereto.

Having thus described my invention, the following is what I claim as new therein and desire to secure by Letters Patent:—

1. The process of preparing a transfer material for receiving printing impressions which comprises applying at and circumjacent to the place of impression an agent for removing moisture from the transfer material.

2. The process of preparing a transfer material for receiving printing impressions which comprises applying immediately prior to the act of making an impression a moisture-removing agent at the place of impression.

3. The process of preparing a transfer material for receiving printing impressions which comprises applying at and circumjacent to the place of impression immediately prior to the act of making an impression a moisture-removing agent.

4. The process of preparing a transfer material for receiving printing impressions which comprises applying moisture-removing air or gas at the place of impression immediately prior to the act of making an impression.

5. The process of preparing a transfer material for receiving printing impressions which comprises desiccating air or other gas and directing a current of said air or gas upon and over the transfer material at the place of impression immediately prior to the act of making an impression.

6. The process of preparing a transfer material for receiving printing impressions which comprises heating air or other gas and directing a current of said air or gas upon and over the transfer material at the place of impression immediately prior to the act of making an impression.

7. The process of preparing a transfer material for receiving printing impressions which comprises maintaining at and adjacent to the place of impression an agent for neutralizing the hygroscopic action of the transfer material.

8. The process of preparing a transfer material for receiving printing impressions which comprises maintaining at and adjacent to the place of impression an atmosphere for neutralizing the hygroscopic action of the transfer material.

GEO. R. CORNWALL.
